UNITED STATES PATENT OFFICE.

ERIK GEORG ERICKSON, OF BAKER, OREGON.

WINDOW-COUNTERBALANCE.

1,373,955.

Specification of Letters Patent. Patented Apr. 5, 1921.

Application filed August 11, 1919. Serial No. 316,701.

To all whom it may concern:

Be it known that I, ERIK GEORG ERICKSON, a citizen of the United States, residing at Baker, in the county of Baker and State of Oregon, have invented new and useful Improvements in Window-Counterbalances, of which the following is a specification.

This invention relates to window construction and has for its primary object to 10 simplify the construction and arrangement of a counter-balanced window sash.

Another object of the invention is to provide novel means for connecting the upper 15 sash with the lower sash to provide for simultaneous movement thereof, so that when the lower sash is raised, the upper sash will be correspondingly lowered and vice versa.

20 A further object is the provision of novel means for securing the cord employed for connecting the sashes, to the sash, the said means permitting of a quick and accurate adjustment of the cord so as to compensate for shrinkage and expansion of the same.

Other objects and advantages of the invention will appear as the following description is read in connection with the accompanying drawings.

30 In the drawings:

Figure 1 is an elevation of a window with the invention applied thereto.

Fig. 2 is a horizontal sectional view of the same.

35 Fig. 3 is a vertical section.

Fig. 4 is an enlarged section through the adjustable connection between the cord and the sash.

40 Fig. 5 is a detail perspective of the cord carried member.

Fig. 6 is a similar view of the perforated plate.

Fig. 7 is a view of a spring wire member for threading cord through the pulleys.

45 Referring to the drawings in detail, like characters of reference denote corresponding parts throughout the several views.

In illustrating the invention, there is shown a window casing, which is indicated at 10. Mounted for sliding movement within this casing in the usual manner, is an upper sash 11 and a lower sash 12.

Mounted upon the top of the frame 10,

near each side thereof, is a sheave, which includes a grooved pulley 13 and a bracket 55 or casing 14, the latter being secured upon the window frame by screws or similar fastening devices 15. Operating over the pulleys 13, is a sash cord 16, the latter passing through openings 17 in the top of the 60 frame 10. One end of each of the cords 16 is permanently secured to each side of the upper sash 11 near the top thereof, as indicated at 18, while the opposite end is adjustably secured to the adjacent side of the 65 lower sash, also near the top.

This last mentioned securing means is of novel construction and permits of an adjustment so as to properly regulate the connection between the sashes, to allow for 70 shrinking and stretching of the cord. This adjusting means comprises a strip of metal 19, which is transversely curved and secured to the lower sash within a socket or notch, as indicated at 20. The end of the strip 75 19 extends above the top of the sash and is provided with spaced openings or perforations 21. Clamped upon the end of the cord 16, is a hook member which comprises a substantially cylindrical body portion 22 80 and a projection which is bent to form a hook 23, the latter being adapted for insertion in any one of the openings 21 to adjustably connect the end of the cord to the sash. By this means proper adjustment 85 may be effected at any time, so as to compensate for shrinkage and expansion of the cord.

In Fig. 7 there is illustrated a spring wire member 24, which is provided upon one end 90 with a hook 25, for threading the cord through the pulleys. The hook 25 is inserted in the end of the cord and the spring wire member threaded through the pulley, whereupon its end may be grasped and the 95 cord pulled through.

The invention is susceptible of various changes in its form, proportions and minor details of construction and the right is herein reserved to make such changes as 100 properly fall within the scope of the appended claims.

Having described the invention, what is claimed is:

The combination with a window includ- 105 ing a casing and upper and lower sashes

slidably mounted therein, a sheave mounted upon the top of the frame near each side thereof, and a cable passing over each of said sheaves, and having one end permanently secured to the upper sash, perforated plates secured to and extending above the upper end of the lower sash, a sleeve se-

cured to the opposite end of said cable, with a reduced extension projecting beyond the lower end of the sleeve, and terminating to 10 provide a hook to be interchangeably received by said perforations.

In testimony whereof I affix my signature.

ERIK GEORG ERICKSON.
